UNITED STATES PATENT OFFICE

2,590,866

HEAT EXCHANGE APPARATUS

John A. Jost, Westfield, and Edward Vogt, Elizabeth, N. J., assignors to Foster Wheeler Corporation, New York, N. Y., a corporation of New York

Continuation of abandoned application Serial No. 476,880, February 24, 1943. This application April 14, 1948, Serial No. 22,796

5 Claims. (Cl. 257—240)

1

This invention relates to heat exchange apparatus, particularly of the shell and tube type.

The invention provides novel heat exchange apparatus which is compact, is useful for high pressure work although not limited thereto, and is capable of being quickly and easily cleaned.

The invention will be understood from the following description when considered in connection with the accompanying drawings forming a part thereof, and in which:

Fig. 1 is an elevational view with parts in section, of a floating head heat exchanger embodying the invention;

Fig. 2 is an elevational view of the left hand end of the device, as viewed in Fig. 1;

Fig. 3 is an elevational view of the right hand end of the device, as viewed in Fig. 1;

Figs. 4, 5, 6, 7, and 8 are sectional views taken respectively on lines 4—4, 5—5, 6—6, 7—7, and 8—8 of Fig. 1;

Fig. 9 is a horizontal sectional view of the left hand end portion of the device, as viewed in Fig. 1 and taken on line 9—9 of Fig. 1;

Fig. 10 is a sectional view taken on line 10—10 of Fig. 6, and

Fig. 11 is an elevational view with parts in section, of a heat exchange device embodying the invention and having fixed tube sheets.

Like characters of reference refer to the same or to similar parts throughout the several views.

Referring to Figs. 1 to 10 of the drawings, the heat exchanger includes a cylindrical shell 10 having a flange 11 at one end, to which is detachably secured a fixed tube sheet 12, and a floating head at the other end comprising a movable tube sheet 13 and a cylindrical extension 14 of an outside diameter slightly smaller than the inside diameter of the shell 10, to permit the extension 14 to move axially within the shell toward and from the fixed tube sheet 12. A plurality of tubes 15 extend through the shell between the fixed and movable tube sheets 12 and 13. To prevent leakage between the shell and the extension 14 of the floating head, a packing gland is provided which comprises an annulus 16 welded to the end of the shell 10 and which has an inwardly projecting flange 17 in slidably engagement with the outer periphery of the extension 14 of the floating head. The packing 18 is disposed between the annulus 16 and the extension 14, and the packing is retained in position by an adjusting ring 19 having a lateral flange 20 which is movable in the space between the annulus 16 and the extension 14. Pressure on the packing is ad-

2

justed by turning nuts 21 on bolts 22. Fluid is introduced into the shell through an inlet nozzle 23 and is withdrawn from the shell through an outlet nozzle 24. If desired, the flow of fluid through the shell may be reversed and it may be introduced through nozzle 24 and withdrawn through nozzle 23. The shell is provided with a wrapper baffle 25 which confines the flow of fluid in the shell substantially to the space occupied by the tubes 15. A plurality of spaced baffles 26 causes the fluid in the shell to flow in a tortuous path over the tubes therein. The shell is provided with a vent 27 and with a drain 28.

In the embodiment of the invention selected for illustration in Figs. 1 to 10, the tubes 15 are connected at their ends to provide for the flow of fluid through the tubes serially, with each tube providing a single pass through the heat exchanger. The return connections at the fixed tube sheet end of the heat exchanger, as well as the inlet and outlet tube connections, are provided by a channel member 29, and the return connections at the floating tube sheet end are provided by a channel member 30. Channel member 29 has an inlet nozzle 31 and an outlet nozzle 32 which extend from the annular periphery of the member. The inlet nozzle connects with one end of a curved passage 33 in the channel member 29 the other end of which connects with the tube 15 constituting the first pass through the exchanger. Outlet nozzle 32 similarly communicates with a curved passage 34 which also connects with the tube providing the last pass through the exchanger. Channel member 29 is provided with a plurality of return channels 35 which are arranged and disposed to connect the ends of adjacent tubes to provide for series flow of the fluid through the tubes in the shell, as indicated in Fig. 4. Channel member 30 is similarly provided with a plurality of return channels 36, Figs. 8 and 9, which connect the ends of adjacent tubes at the floating head ends thereof to provide for series flow of the fluid through the tubes.

The channel members 29 and 30 are detachably secured to the fixed and floating tube sheets respectively, by means which permit the channel members to be removed and replaced readily. As shown, such retaining means comprises a cover 37 for the fixed tube sheet channel member 29, which is removably secured to the shell 10. The cover 37 is provided with laterally and inwardly extending arms 38 and 39, Figs. 3, 4 and 5, the inner portions of which are adapted to be received between spaced knuckles 40 and 41 re-

spectively, which are secured to opposite sides of the flanged portion of the shell 10. The registering parts of the arms and knuckles have registering apertures through which a hinge pin 42 passes, to removably secure the cover 37 to the shell 10 with the channel member 29 between the fixed tube sheet 12 and the cover. Cover 37 is provided with a plurality of set screws 44, the inner ends of which engage the outer face of the channel member 29. Tightening of these set screws when the cover member 37 is in position on the shell, will force the channel member 29 against the tube sheet 12 or a gasket thereon and will seal the return connections between the tubes 15. A plurality of bolts 45 extend through the cover 37 and thread into the channel member 29 to secure the channel member to the cover member so that the former may be swung to open position and returned to closed position simultaneously with the cover member. It will be understood that when it is desired to remove the channel and cover members, one of the pins 42 may be removed and the channel and cover members may be swung about the other pin 42 as a hinge to open position, or if desired, both pins 42 may be removed and the channel and cover members may be removed entirely from the shell.

At the floating tube sheet end of the heat exchanger, the channel member 30 is held in position by a cover member 46, like cover member 37, and having laterally and inwardly extending arms 48 and 49 at opposite sides thereof, the inner ends of which are disposed between spaced knuckles 50 and 51 and are secured thereto by pins 53 which extend through registering apertures in the arms and knuckles. The cover member 46 is provided with a plurality of set screws 54 to force the channel member against the gasket 55 and the floating tube sheet 13, and a plurality of bolts 56 to fasten the channel member to the cover member. However, to permit the tube bundle to be withdrawn from the shell through the right hand end thereof, as viewed in Fig. 1, the knuckles 50 and 51 are secured to a hinge ring 57 which is detachably secured to the floating tube sheet 13. Referring particularly to Figs. 9 and 10, the annular periphery of the floating tube sheet 13 is provided with an annular recess 58 which receives an inwardly extending annular flange of a split ring 59 which overlies the outer end portion of the floating tube sheet 13. The hinge ring 57 has a groove 60 in the outer part of its inner peripheral portion to receive the split ring, as shown particularly well in Fig. 9. To insure the correct positioning of the hinge ring 57 on the tube sheet and to prevent rotation of the ring, the tube sheet and hinge ring are provided with diametrically opposed keyways, each of which receives a key 61 which is retained in position by a set screw 62 threaded in the hinge ring. With this arrangement, the cover member 46 and the channel member 30 may be removed and replaced in the manner described in connection with the corresponding parts at the opposite end of the heat exchanger, and the hinge ring may be removed from the floating tube sheet by loosening the set screws 62, sliding the hinge ring toward the opposite end of the heat exchanger to an extent which will permit the removal of the split ring 59, after which the hinge ring may be withdrawn from the tube sheet. To return the hinge ring to operative position, it is placed on the tube sheet 13 and is moved to a position which will permit the insertion of the keys 61 in

their keyways, assuming they have been removed previously, and the insertion of the split ring, after which the hinge ring is moved into operative position with the keys 61 in their keyways, and the set screws 62 are tightened.

The form of the invention shown in Fig. 11, is similar to the form shown in Figs. 1 to 10, excepting that the tube sheets are fixed at both ends and an expansion joint is employed in lieu of a packing gland. In Fig. 11, the tube sheet 63 has a cylindrical extension 64 which is provided with a flange 65 of sufficiently large diameter to receive within it the end of the shell 10. The flange 65 is secured to one end of an expansion joint 66, the other end being fixed to a member 67 which is welded to the outer wall of the shell 10. A channel member 68 having a plurality of channels similar to the channels 36, is held in position against the tube sheet, or a gasket on the tube sheet, by a cover member 69 similar to the cover member 46, and which is provided with a plurality of set screws 70. The cover member 69 is detachably secured to the shell 10 through laterally and inwardly extending arms 71 which are received between spaced knuckles 72 on the shell. A pin 73 passes through registering apertures in each of the arm and knuckle groups at each side of the tube sheet and retains the cover plate in position. The cover plate and channel member are removed and replaced in the manner previously described in connection with the removal and replacement of the channel member 29 and cover plate 37.

From the foregoing it will be perceived that heat exchangers embodying the invention are compact, and that the tubes and the parts associated with the tubes, as well as other parts of the exchangers, are readily accessible for cleaning and repair.

The present application is a continuation of application Serial No. 476,880 filed February 24, 1943, now abandoned.

Since changes may be made in the form, location and relative arrangement of the several parts of the apparatus disclosed without departing from the principles of the invention, it will be understood that the invention is not to be limited excepting by the scope of the appended claims.

What is claimed is:

1. Heat exchange apparatus comprising a shell, tube sheets, tubes extending between the tube sheets, a channel member associated with a tube sheet and having a channel therein communicating with the ends of a plurality of tubes to provide a return connection for the tubes, a cover member adapted to be positioned on the outer side of the channel member, a removable ring for the outside of the shell, a split ring engaging the removable ring and the shell for removably attaching the removable ring to the shell, key means for the removable ring to retain it in proper position on the shell, means for removably connecting the cover member to the removable ring, and means for forcing the channel member toward the tube sheet with which it is associated.

2. Heat exchange apparatus comprising a shell having a groove therein adjacent one end thereof, tube sheets, tubes extending between the tube sheets, a channel member associated with a tube sheet and having a channel therein communicating with the ends of a plurality of tubes to provide a return connection for the tubes, a cover member adapted to be positioned on the outer side of the channel member, a removable ring

for the outside of the shell, a split ring engaging the groove in the shell and extending above the surface of the shell for removably attaching the removable ring to the shell, the removable ring having engaging means adapted to engage the portion of the split ring extending above the surface of the shell on the side of said split ring furthest from said one end of the shell, knuckles on the removable ring, each knuckle having an extension with an aperture therein, which extension projects toward the cover member, positioning means for insuring the proper position of the channel member in relation to said end of the tubes, apertured arms on the cover member extending toward extensions on the knuckles on the removable ring, pins passing through the apertures in the extensions on the knuckles, arms for removably connecting the cover member to the removable ring, said extensions and said arms being of a length to form a space between the cover member and the adjacent tube sheet in which space the channel member is disposed, set screws carried by the cover member and adapted to engage the channel member for forcing the latter toward the tube sheet and for drawing the engaging means into tight engagement with the split ring and the split ring into tight engagement with said groove when the tube sheet and channel member are in engagement, and threaded members for detachably securing the channel and cover members together.

3. Heat exchange apparatus comprising a shell, tube sheets adjacent opposite ends of the shell and closing said shell in a fluid-tight manner, tubes extending between the tube sheets, a channel member associated with a tube sheet and having a channel therein communicating with the ends of a plurality of tubes to provide a return connection for the tubes, a cover member outside the shell adapted to be positioned on the outer side of the channel member and substantially coextensive therewith, a separate removable ring for the outside of the shell, means for removably attaching the ring to the shell, means for connecting the cover member to the removable ring, and a plurality of set screws carried by the cover member in an area substantially coextensive with said channel member, said set screws being so spaced from one another throughout said area that the set screws exert a force on the channel member which forces said member throughout its area toward and into engagement with the tube sheet.

4. Heat exchange apparatus comprising a shell, tube sheets, tubes extending between the tube sheets, a channel member associated with a tube sheet and having a channel therein communicating with the ends of a plurality of tubes to provide a return connection for the tubes, a cover member adapted to be positioned on the outer side of the channel member, a removable ring for the outside of the shell, a split ring mounted on the shell for removably attaching the removable ring to the shell, the shell having engaging means

- adapted to engage the split ring along the side thereof toward the cover member and the removable ring having other engaging means adapted to engage the split ring along the side of the split ring opposite said side toward the cover, means for removably connecting the cover member to the removable ring, and means cooperating with the cover means and the channel for forcing the channel member toward the tube sheet with which it is associated and for drawing said engaging means and said other engaging means into tight engagement with said side and said opposite side of the split ring when the tube sheet and channel member are in engagement.
5. Heat exchange apparatus comprising a shell, tube sheets, tubes extending between the tube sheets, a channel member associated with a tube sheet and having a channel therein communicating with the ends of a plurality of tubes to provide a return connection for the tubes, a cover member adapted to be positioned on the outer side of the channel member, a removable ring for the outside of the shell, a split ring mounted on the shell for removably attaching the removable ring to the shell, the shell having engaging means adapted to engage the split ring along the side thereof toward the cover member and the removable ring having other engaging means adapted to engage the split ring along the side of the split ring opposite said side toward the cover, knuckles having apertures on the removable ring, apertured arms on the cover member, pins passing through the apertures in the knuckles and arms for hingedly connecting the cover member to the ring, and means cooperating with the cover means and the channel for forcing the channel member toward the tube sheet with which it is associated and for drawing said engaging means and said other engaging means into tight engagement with said side and said opposite side of the split ring when the tube sheet and channel member are in engagement.
